UNITED STATES PATENT OFFICE

HEINRICH SCHÜNEMANN, OF BERLIN-SPANDAU, GERMANY, ASSIGNOR TO NEUER-BURG'SCHE VERWALTUNGSGESELLSCHAFT, M. B. H., OF COLOGNE-ON-THE-RHINE, GERMANY, A JOINT-STOCK COMPANY

MACHINE FOR FIXING TUBULAR MOUTHPIECES TO CIGARETTES

Application filed December 23, 1929, Serial No. 416,142, and in Germany December 27, 1928.

My invention relates to improvements in machines for fixing tubular mouthpieces to cigarettes, and the object of the improvements is to provide a machine by means of which the tubular wrapper is fixed to a complete cigarette. Another object of the improvements is to provide a machine by means of which a large number of cigarettes can be provided with their mouthpieces, the efficiency of the machine corresponding to the output of a cigarette making machine. Another object is to provide a machine which is adapted to apply tapering mouthpieces to the cigarettes, which are provided at their ends with a strengthened mouth. With these objects in view my invention consists in providing a pair of carriers moving in unison one beside the other and provided with pairs of aligned channels adapted to contain respectively a cigarette and a tubular mouthpiece, and plungers adapted to engage the said channels from opposite sides for shifting the cigarettes and their mouthpieces into engagement with each other.

For the purpose of explaining the invention an example embodying the same has been shown in the accompanying drawings in which the same reference characters have been used in all the views to indicate corresponding parts. In said drawings,

Fig. 1 is a longitudinal sectional elevation showing a cigarette and a tubular mouthpiece separate therefrom,

Fig. 2 is a similar sectional elevation showing the cigarette having the mouthpiece applied thereto,

Fig. 3 is an elevation showing the machine,

Fig. 4 is an elevation looking from the right in Fig. 1,

Fig. 4a is a detail sectional elevation on an enlarged scale illustrating one of the channels receiving the tubular mouthpieces,

Fig. 5 is a sectional elevation on an enlarged scale taken on the line 5—5 of Fig. 4,

Fig. 6 is an elevation looking from the left of Fig. 5,

Fig. 7 is a sectional elevation showing the drum for assorting the mouthpieces,

Fig. 8 is a partial plan view of Fig. 7,

Fig. 9 is a plan view showing a rotary disk

receiving the assorted mouthpieces and conveying the same to the apparatus for applying the mouthpieces to the cigarettes,

Fig. 10 is a sectional elevation taken on the line 10—10 of Fig. 9,

Fig. 11 is a sectional elevation on an enlarged scale taken on the line 11—11 of Fig. 4 and showing the apparatus for fixing mouthpieces to the cigarettes,

Fig. 12 is a sectional elevation taken on the line 12—12 of Fig. 11,

Fig. 13 is a sectional elevation taken on the line 13—13 of Fig. 11, some of the parts being broken away,

Fig. 14 is a sectional elevation on an enlarged scale taken on the line 14—14 of Fig. 4 and showing the mechanism for applying glue to the mouthpieces, and

Fig. 15 is a sectional elevation taken on the line 15—15 of Fig. 14, some parts being broken away.

Fig. 16 is a detail view of the mouthpiece conveying means.

By means of the machine shown in the figures tubular mouthpieces M are fixed to cigarettes Z such as are shown in Figs. 1 and 2, the said cigarette being first slightly contracted at one end before applying the mouthpiece thereto. As appears from the said figures, the mouthpiece is tapering in form, and it may be made from any material, such for example as pressed wood, rolled veneer, cardboard, etc.

Referring to Figs. 3 and 4, the machine comprises the following mechanisms:

First, an apparatus for assorting the mouthpieces and conveying the same into the apparatus for fixing the same to the cigarettes, the said apparatus comprising a drum A adapted to receive the non-assorted mouthpieces and to arrange the same with their reduced ends directed downwardly, a conveying device B in the form of a pair of endless tapes moving longitudinally of the drum A and adapted to receive the mouthpieces delivered therefrom, a storing device C in the form of a rotary disk formed with a spiral groove adapted to have the cigarettes placed thereon, a chute or channel D for receiving the mouthpieces from the storing device C

and delivering the same to the assembling apparatus K, second, an apparatus for applying glue to the tubular mouthpieces at the ends to be fixed to the cigarettes, the said gluing apparatus comprising a box E, a rotary disk F adapted to receive glue from the box E, and plungers G adapted to be coated with the glue and to apply the same to the mouthpieces, third, an apparatus for uniting the cigarettes and the mouthpieces comprising a drum H formed circumferentially with axial channels adapted to receive the cigarettes, plungers J reciprocating in said channels for shifting the cigarettes towards the mouthpieces, and the aforesaid assembling apparatus in the form of an endless chain K adapted to receive the mouthpieces and plungers L adapted to shift the said mouthpieces from the endless chain towards the cigarettes and to deliver the same on an endless conveying band N.

I

Apparatus for assorting and conveying the tubular mouthpieces

As shown in Figs. 1 and 2 the mouthpieces are tapering in form, and therefore they must be assorted so that they are located with their large end in position for being fixed to the cigarettes. The assorting and conveying mechanism is shown in Figs. 5 and 6, and it comprises a drum A provided with two end walls 1 and 2 and having its cylindrical wall provided by rods 3 arranged in groups say of three rods located in close relation to one another, the groups being spaced from one another, as is shown at 4. The drum is provided with a tubular hub 5 rotatably mounted on a fixed tubular axis 6 secured to the frame 7.

The drum A is adapted to be rotated by means of a gear wheel 8 fixed to the end wall 1 and meshing with a pinion 9 adapted to be rotated through the intermediary of gear wheels 10, 11 and 12 from a driving shaft 13. Into the said drum the mouthpieces are delivered by means of a chute 14. Within the said drum A a cylindrical brush 15 is eccentrically mounted which is rotatable on a stationary axis 16 secured to a disk 17 fixed to the tubular axis 6. The hub 18 of the brush 15 is rotatable on the axis 16 and it is adapted to be rotated by means of a gear wheel 19 and a pinion 20 secured to the driving shaft 13. By the said gear wheels the drum 15 is rotated relatively to the drum A. The cylindrical wall of the drum A is partly covered by a concentric jacket 22 formed at its bottom with a bevelled edge 21, as is best shown in Figs. 7 and 8. The brush 15 is mounted within the drum A so that the distance between the same and the jacket 22 is not larger than the diameter of the mouthpieces. Therefore only those mouthpieces are held back by the cylindrical brush 15, which are

located on the groups of rods 3, while the mouthpieces falling into the spaces 4 are carried along by the rods 3 and drop from the drum when passing the bevelled edge 21 of the jacket. The tubular mouthpieces M delivered from the drum drop into the conveying device B comprising a pair of endless wires 23, the distance between the adjacent portions of the said wires being larger than the smallest diameter and smaller than the largest diameter of the mouthpieces, so that the mouthpieces engaged between the wires are directed with their reduced ends downwardly. By the said wires the said mouthpieces are delivered to an inclined chute 25 conveying the same with their reduced ends forwardly to the storing disk C. To assist the movement of the mouthpieces within the channel 25 I provide a nozzle 26 for delivering a blast of air through the chute.

The storing device C consists of a stationary ring 27 formed at its top face with a spiral groove 28, which is broader at its top than at its bottom, as is shown in Figs. 4a and 10, so that the rear or reduced ends of the mouthpieces bear on the bottom of the groove, while the forwardly directed large ends are engaged between the inclined side walls of the groove. Above the ring 27 there is a rotary disk 29 provided at its bottom face with bristles 30, by means of which the tubular mouthpieces delivered from the chute 25 into the groove 28 are continuously moved forwardly. From the inner end 31 of the said groove the mouthpieces are delivered with their reduced ends forwardly into the chute D, by means of which they are conveyed to the endless chain K. To assist the rapid movement of the mouthpieces I prefer to provide a nozzle for blowing a blast of air through the channel D, the blast of air acting incidentally to separate the mouthpieces from each other and to avoid nesting thereof.

By providing the storing ring 27 it is not necessary to operate the chain K exactly at the rate as the mouthpieces are delivered from the assorting drum A, because any excess of mouthpieces can be temporarily stored on the said ring. In some cases I provide regulating means for temporarily arresting the assorting drum when the storing ring has been filled with mouthpieces. In the figures such regulating means have not been illustrated.

In connection with the foregoing attention is directed to Fig. 16 in which the means for feeding the mouthpieces individually are shown on an enlarged scale. In this figure travelling wires 23 convey the hollow mouthpieces M which drop from the drum A to a point beneath the air blast pipe or nozzle 26 and above the chute 25. The blasts of air separately and successively assist in the passage of the mouthpieces through the chute.

to the root surfaces 28 of the storing ring 27 of the storing device C. Obviously the passage of the mouthpieces between the storing ring 27 and the mouthpiece chain K may be accelerated by a blast of air introduced into the chute or channel D. For this purpose it may be assumed that the inlet of the pipe D, wherein the individual mouthpiece drops which is conveyed by the spiral groove C is widened in the same manner as the inlet of the chute 25 and above this widened inlet a blast air pipe may be provided similar to the blast air nozzle 26.

fixed to the plungers 46. At their inner ends the said slides carry rollers 55 engaging in a stationary cam groove 56 made in a ring 57 having its hub 58 fixed to a portion 59 of the frame work of the machine. When rotating the drum 38 the rollers 55 of the slides travel in the groove 56, so that the slides are shifted longitudinally of the drum in accordance with the pitch of the said groove, thus driving the glued heads into the ends of the 75 mouthpieces projecting from the tubular bolts 35 of the chain K and applying thereto glue while being rotated.

15

II

Apparatus for gluing the tubular mouth-pieces

For fixing the mouthpieces to the cigarettes it is necessary to apply glue to the large ends thereof, and for this purpose gluing means are provided in my improved machine which cooperate with the chain K receiving the mouthpieces from the channel D. The said chain is trained on three sprocket wheels 32, 33 and 34. Its links are jointed by tubular bolts 35 adapted to have the tubular mouthpieces M inserted into the same. Preferably I provide springs 36 within the 20 said tubular bolts for holding the inserted mouthpieces in position. The chain travels in the direction of the arrow 37 shown in Fig. 4. The mouthpieces inserted into the tubular bolts 35 are conveyed forwardly for 25 revolving around the sprocket wheel 34. Co-axially of the said sprocket wheel a drum 38 is mounted, which drum has the same circumferential velocity as the chain K, the sprocket wheel and the drum being both 30 mounted on a shaft 39, as is shown in Fig. 14. The shaft 39 is connected by gear wheels 40 and 41 with a pinion 42 meshing with an internal gear wheel 43 rotatable on the shaft 39. The said internal gear wheel is provided with external teeth 44 engaged by pinions 45 secured to plungers 46, the said 40 plungers being rotatable and axially shiftable in flanges 47 and 48 of the drum 38. The plungers 46 are provided with heads 49 having a diameter nearly equal to the diameter of the tubular mouthpieces, and they are adapted to be coated with glue taken from the box E by means of the gluing disk F shown in Figs. 3 and 4, the heads of the 45 plungers being rotated in contact with the said disk for taking glue therefrom. The glue applied to the heads of the plungers is transmitted to the ends of the mouthpieces, for which purpose the plungers 46 having 50 their heads 49 coated with glue are shifted in axial direction. For thus shifting the plungers slides 51 are provided which are guided in longitudinal slots 50 of the rotary drum 38, which slides are provided with 55 noses 52 engaging between collars 53 and 54

III

Apparatus for fixing the mouthpieces to the cigarettes

While the tubular mouthpieces are conveyed to the chain K and glue is applied thereto the cigarettes are conveyed into position for having the mouthpieces applied thereto, and they are taken either directly from the cigarette making machine or from a storage receptacle. The cigarettes are placed on the drum H and they are contracted at one of their ends so that the tubular mouthpiece can be readily placed thereon.

In the construction shown in Fig. 4 the cigarettes are taken from a storage receptacle 60, and they are placed on an endless conveying band 61 directly or indirectly delivering the same into the open chambers or troughs 62 of the drum 63 mounted coaxially of the sprocket wheel 32, the said drum being rotated together with the sprocket wheel 32 from the shaft 64.

As the drum 63 rotates in the direction of the arrow 37 shown in Fig. 4 the cigarettes located in the channels 62 are pushed, by axially reciprocating plungers 65, into a ring 66 provided with bores corresponding in diameter to the diameter of the cigarettes. The plungers 65 are thus reciprocated in pairs, the pair of plungers 65 being secured to a slide 67 mounted on guide rods 68 and acted upon by a spring 69 tending to pull the same inwardly and to the right in Fig. 11 and with a roller 70 into engagement with a cam disk 71. Thus, upon rotation of the drum 63 the pair of plungers 65 is axially shifted at the desired period of time.

At the bottom part of Fig. 11 the pair of plungers 65 and the cigarettes Z engaged thereby have been shown in the right-hand position, the cigarette being inserted into the bore 72. For contracting the end of the cigarettes Z at the right of the bores 72 spring rings 73 are provided the inner diameter of which is slightly smaller than the diameter of the cigarettes, and the said spring rings are adapted to be spread apart by conical plungers 74 to permit the cigarettes Z to be inserted into the same by the plungers 65. The conical plungers 74 take part in the ro-

tary movement of the drum 63, and they are shifted in axial direction by pins 75 projecting therefrom and engaging fixed stop members such as rollers 76.

5 The plungers 65 and 74 are controlled by the cam 71 and the stop members 76 which are disposed relatively to each other so that at first the spring rings 73 are spread by the conical plungers 74, and thereafter the plungers 65 are advanced for inserting the cigarettes into the rings 73, whereupon the conical plungers 74 are retracted from the spring rings permitting the said spring rings to contract and to compress the ends of the cigarettes, as is shown at the bottom part of Fig. 11. Thereafter the cigarettes which are held with their ends contracted in the spring rings 73 are further moved with the rotary drum, and they are combined with the glued mouthpieces contained in the tubular bolts of the chain K. For this purpose coaxially of the sprocket wheel 32 and the drum 63 and at the side opposite to the plungers 65 revolving plungers 77 are provided, the said plungers 25 being mounted on a rotary disk 78 secured to the shaft 64. The said plungers 77 are advanced when a cigarette has been fixed within the spring ring 73 and is in alignment with a mouthpiece, the said mouthpiece M 30 being first shifted forwardly by the head of the plunger 77 and through the hollow plunger 74 and on the contracted end of the cigarette while simultaneously spreading the spring ring 73. In this operation the plunger 65 provides a stop for holding the cigarette in position while the plunger 77 is being advanced. Thereafter the plungers 65 are retracted by the cam disk 71. The plungers 77 are mounted in pairs on slides 80 shiftable 35 on guide rods 81 of the disk 78 and controlled by a cam groove 82 engaging rollers 83 carried by the slides.

At the end of the return movement of the plungers 65 the plungers 77 are further shifted forwardly, thus shifting the cigarettes Z and the mouthpieces fixed thereto in the direction of the arrow 79 and out of the channels 72 and into the channels 62 of the drum 63. Upon further rotation of the drum 63 the cigarettes having the mouthpieces fixed thereto drop from the open channels 62 and onto a conveying device such as an endless band N.

My improved machine may be directly connected with a cigarette making machine, or the cigarettes may be made on a separate machine.

While in describing the invention reference has been made to a particular example embodying the same I wish it to be understood that my invention is not limited to the construction shown in the drawings, and that various changes may be made in the general arrangement of the apparatus and the construction of its parts without departing from the invention.

I claim:

1. A machine for fixing tubular mouthpieces to cigarettes, comprising a pair of carriers mounted for moving in unison one beside the other and provided with pairs of aligned channels adapted to contain respectively a cigarette and a tubular mouthpiece therefor, operating means for said carriers, and means for pushing the mouthpieces on the cigarettes. 70 75

2. A machine for fixing tubular mouthpieces to cigarettes, comprising a pair of carriers mounted for moving in unison one beside the other and provided with pairs of aligned channels adapted to contain respectively a cigarette and a tubular mouthpiece therefor, operating means for said carriers, plungers adapted to engage the cigarettes and mouthpieces of a pair from opposite sides thereof and to shift the same on each other, and means for operating said plungers. 80 85

3. A machine for fixing tubular mouthpieces to cigarettes, comprising a pair of carriers mounted for revolving in unison one beside the other and provided with pairs of aligned channels adapted to contain respectively a cigarette and a tubular mouthpiece therefor, operating means for said carriers, and means for pushing the mouthpieces on the cigarettes. 90 95

4. A machine for fixing tubular mouthpieces to cigarettes, comprising a pair of carriers mounted for moving in unison one beside the other and provided with pairs of aligned channels adapted to contain respectively a cigarette and a tubular mouthpiece therefor, operating means for said carriers, plungers movable with said carriers and adapted to engage the cigarettes and mouthpieces of a pair from opposite sides thereof and to shift the same on each other, and means for operating said plungers. 100 105

5. A machine for fixing tubular mouthpieces to cigarettes, comprising a rotary drum provided circumferentially with axial grooves adapted to receive cigarettes, a carried mounted for revolving coaxially of said drum and in unison therewith and provided with axial channels disposed for moving in alignment with said grooves and to receive mouthpieces, plungers mounted for moving with said drum in position for shifting the cigarettes placed in said grooves towards said channels, a stationary cam controlling the movement of said plungers, means for driving said drum and carrier, and means for shifting said mouthpieces towards said cigarettes. 110 115 120

6. A machine for fixing tubular mouthpieces to cigarettes, comprising a pair of carriers mounted for moving in unison one beside the other and provided with pairs of aligned channels adapted to contain respectively a cigarette and a tubular mouthpiece therefor, operating means for said carriers, 125 130

means for contracting the cigarettes at the end receiving the mouthpieces, and means for pushing the mouthpieces on the cigarettes.

7. A machine for fixing tubular mouthpieces to cigarettes, comprising a pair of carriers mounted for moving in unison one beside the other and provided with pairs of aligned channels adapted to contain respectively a cigarette and a tubular mouthpiece therefor, operating means for said carriers, rings formed of coiled springs and having a diameter smaller than the cigarettes and located in position for having said cigarettes inserted into the same with the ends receiving the mouthpieces, plungers for spreading said rings before inserting the cigarettes and releasing the same after inserting the cigarettes, cam members controlling said plungers, and means for pushing the mouthpieces on the cigarettes.

8. A machine as claimed in claim 1, in which the carrier for the mouthpieces is in the form of an endless chain comprising tubular members adapted to receive the mouthpieces.

9. A machine for fixing tubular mouthpieces to cigarettes, comprising a pair of carriers mounted for moving in unison one beside the other and provided with pairs of aligned channels adapted to contain respectively a cigarette and a tubular mouthpiece therefor, operating means for said carriers, means for applying glue to the ends of the mouthpieces to be fixed to the cigarettes, and means for pushing the mouthpieces on the cigarettes.

10. In a machine for fixing mouthpieces to cigarettes, the combination, with the mechanism for fixing the mouthpieces to the cigarettes, of a rotary assorting drum having its cylindrical wall made from rods, a cylindrical brush within said drum and rotatable relatively thereto, a jacket partly covering said drum and spaced from said rods and formed with an inclined edge adapted to engage the mouthpieces passing between said rods, and means for conveying the mouthpieces delivered from said drum to the mechanism for fixing the same to the cigarettes.

11. In a machine for fixing mouthpieces to cigarettes, the combination, with the mechanism for fixing the mouthpieces to the cigarettes, of a rotary assorting drum having its cylindrical wall made from rods, a cylindrical brush within said drum and rotatable relatively thereto, a jacket partly covering said drum and spaced from said rods and formed with an inclined edge adapted to engage the mouthpieces between said rods, and means for conveying the mouthpieces delivered from said drum to the mechanism for fixing the same to the cigarettes, said means comprising a pair of endless bands moving longitudinally of said drum at the delivery end thereof and spaced from each other a

distance smaller than the largest diameter and larger than the smallest diameter of the mouthpieces.

12. In a machine for fixing mouthpieces to cigarettes, the combination, with the mechanism for fixing the mouthpieces to the cigarettes, of a rotary assorting drum having its cylindrical wall made from rods, a cylindrical brush within said drum and rotatable relatively thereto, a jacket partly covering said drum and spaced from said rods and formed with an inclined edge adapted to engage the mouthpieces passing between said rods, and means for conveying the mouthpieces delivered from said drum to the mechanism for fixing the same to the cigarettes, said means comprising a disk formed with a spiral groove in position for having the mouthpieces deposited therein and a brush in position for engaging the mouthpieces placed in said groove, and means for rotating said brush and disk relatively to each other in a direction for shifting the mouthpieces through said spiral groove.

13. A machine as claimed in claim 1, in which the carrier for the mouthpieces is in the form of an endless chain comprising tubular members adapted to receive the mouthpieces, and springs provided internally of said tubular members so as to hold the mouthpieces.

14. A machine as claimed in claim 1, in which the carrier for the mouthpieces is in the form of an endless chain comprising tubular members adapted to receive the mouthpieces, two sprocket wheels on which said chain is trained, glue applying plungers revolving coaxially of and in unison with one of said sprocket wheels and in alignment with said tubular members, means for applying glue to said plungers, and means for reciprocating said plungers towards and away from the mouthpieces within said tubular members.

15. A machine as claimed in claim 1, in which the carrier for the mouthpieces is in the form of an endless chain comprising tubular members adapted to receive the mouthpieces, two sprocket wheels on which said chain is trained, glue applying plungers revolving coaxially of an in unison with one of said sprocket wheels and in alignment with said tubular members, means for applying glue to said plungers, means for reciprocating said plungers towards and away from the mouthpieces within said tubular members, and means for rotating said glue applying plungers while reciprocating the same, and relatively fixed glue applying means adapted to be engaged by the rotating plungers.

In testimony whereof I hereunto affix my signature.

HEINRICH SCHÜNEMANN.
